UNITED STATES PATENT OFFICE

92,883

DESIGN FOR AN AIRPLANE

George Wilbur Cornelius, Van Nuys, Calif.

Application October 27, 1933, Serial No. 49,567

Term of patent 3½ years

To all whom it may concern:

Be it known that I, GEORGE WILBUR CORNELIUS, a citizen of the United States, residing in Van Nuys, county of Los Angeles, State of California, have invented a new, original, and ornamental Design for Airplanes, of which the following is a specification, reference being had to the accompanying drawing, forming part thereof.

Figure 1 is a plan view of the airplane showing my new design.

Fig. 2 is a side elevational view of the airplane showing my new design.

Fig. 3 is a front elevational view of the airplane showing my new design.

Fig. 4 is a view in perspective of the airplane showing my new design.

I claim:—

The ornamental design for an airplane, as shown.

GEORGE WILBUR CORNELIUS.
